C. C. ABBOTT

DIAPHRAGM SWITCH

Filed July 11, 1919

Inventor:
Charles C. Abbott,
by *Albert G. Davis*
His Attorney.

UNITED STATES PATENT OFFICE.

CHARLES C. ABBOTT, OF PITTSFIELD, MASSACHUSETTS, ASSIGNOR TO GENERAL ELECTRIC COMPANY, A CORPORATION OF NEW YORK.

DIAPHRAGM SWITCH.

Application filed July 11, 1919. Serial No. 310,271.

To all whom it may concern:

Be it known that I, CHARLES C. ABBOTT, a citizen of the United States, residing at Pittsfield, county of Berkshire, State of Massachusetts, have invented certain new and useful Improvements in Diaphragm Switches, of which the following is a specification.

My invention relates to pressure cells, and has for its object the provision of an improved type that will be simple and rugged in construction and at the same time thoroughly reliable and efficient.

More specifically, my invention relates to the type of pressure cell provided with a buckling diaphragm that is actuated by the change of pressure within the cell. Heretofore one of the great difficulties of this type of cell has been to obtain a cell that would remain leak-proof. Usually after the cell had been in operation a short time, the volatile liquid therein would leak from the joint between the cup or dished plate and the diaphragm. It was found that the leaking joint, while caused somewhat by the radial expansion of the diaphragm, was largely due to the fact that it was within the stressed area of the diaphragm. The object of my invention is to provide a pressure cell that overcomes this difficulty. This I accomplish by extending the peripheral portion of the diaphragm over the flange and outside surface of the cell cup and soldering the diaphragm to the cup without the area of stress of the diaphragm. To prevent any injury from the radial expansion of the diaphragm, I provide a frame or casing that closely fits over the flange of the cup and the outside thereof, rigidly holding the diaphragm therebetween. Other objects and purposes of my invention will appear in the course of the following specification, in which I have shown my invention embodied in concrete form for purposes of illustration.

In the accompanying drawing, the figure is a view, partly in elevation and partly in section, illustrating an application of my invention.

Referring to the drawing, 1 is a chamber through which a fluid passes. Adjacent a wall 2 of the chamber is the pressure cell 3 which is affected by the change of temperature of the fluid flowing through the chamber. A switch 4 housed

in the casing 5 is operated by the pressure cell in the manner hereinafter described. The pressure cell 3 is made up of a metallic cup 6 and a diaphragm 7 which is of an elastic metal, preferably phosphor-bronze. It will be seen from the drawing that the peripheral portion 8 of the diaphragm is spun to extend over the flange 9 of the cup 6 and around the outside surface thereof. Since the center of the diaphragm must have a spring temper, and since phosphor-bronze will not spin if it is spring-tempered, it is necessary to anneal the peripheral portion of the diaphragm before spinning it while the center is clamped between chill blocks, after which the center is dished by being struck with a suitable die. The diaphragm having thus been formed is placed over the metallic cup 6 and the peripheral portion 8 of the diaphragm is soldered to the cup 6 on its outside at 10. The soldered joint is therefore without the stressed area of the diaphragm and the pressure cell does not depend upon the spinning for a leak-proof joint. The casing 5 is provided with a flange 11 which fits over the flange 9 and telescopes the cup 6 with the diaphragm therebetween, as shown in the drawing, rigidly securing the diaphragm and preventing any radial expansion thereof. The cup 6 is provided with an opening 12 through which a volatile liquid is poured into the pressure cell, which is hermetically sealed after the air has been exhausted therefrom, in any suitable manner.

It will readily be understood that an increase in the temperature of the fluid passing through the chamber 1 increases the pressure of the cell, causing the diaphragm 7 to buckle and operate the switch 4, which is shown in closed position. Likewise a decrease in the temperature will permit the closing of the switch. Adjustment for different temperature operations is made by using various mixtures of volatile liquids. It will thus be seen that I have provided a pressure cell that has a leak-proof joint without the stress area of the diaphragm, thus remedying one of the main defects in pressure cells as heretofore constructed, and which is also provided with means preventing any injury from the radial expansion of the diaphragm, resulting in a very simple, compact and durable structure.

While I have described my invention as

embodied in concrete form and as operating in a specific manner in accordance with the provisions of the patent statutes, it should be understood that I do not limit my invention thereto, since various modifications thereof will suggest themselves to those skilled in the art without departing from the spirit of my invention, the scope of which is set forth in the annexed claims.

10. What I claim as new and desire to secure by Letters Patent of the United States, is,—
1. A pressure cell comprising a metallic cup, a buckling diaphragm secured thereto to form a leak proof joint and a cover 15 curing the diaphragm to the cup and removable without breaking said joint.
  2. A pressure cell comprising a metallic cup, a buckling diaphragm soldered thereto to form a leak proof joint, and a removable 20 casing securing the diaphragm to said cup so as to protect said joint from strains set up in said diaphragms.
  3. A pressure cell comprising a metallic cup, a buckling diaphragm provided with a 25 cylindrical peripheral portion telescoping said cup, said peripheral portion having its

edge secured to said cup to form a leak-proof joint, and a removable casing fitting over the member thus formed, clamping the peripheral portion of the diaphragm between it and the metallic cup. 30

4. A pressure cell comprising a metallic cup, a buckling diaphragm provided with a cylindrical peripheral portion telescoping said cup, said peripheral portion having its 35 edge soldered to said cup and a removable casing fitting over the member thus formed, clamping the peripheral portion of the diaphragm between it and the metallic cup.

5. A pressure cell comprising a metallic cup, a buckling diaphragm extending over the flange of and over the outside surface of said cup and having its peripheral portion soldered to said outside surface, and a removable casing fitting over the member 40 thus formed, clamping the peripheral portion of the diaphragm between it and the metallic cup. 45

In witness whereof, I have hereunto set my hand this eighth day of July, 1919.

CHARLES C. ABBOTT.
